WITNESS:

UNITED STATES PATENT OFFICE.

FRANK B. VORACEK, OF PORTLAND, OREGON.

AIRPLANE.

Original application filed October 18, 1920, Serial No. 417,535. Divided and this application filed April 18, 1922. Serial No. 555,394.

To all whom it may concern:

Be it known that I, FRANK B. VORACEK, a citizen of the United States, residing at Portland, in the county of Multnomah and 5 State of Oregon, have invented new and useful Improvements in Airplanes, of which the following is a specification.

This invention relates to improvements in airplanes and is a division of an application 10 filed by me Oct. 18, 1920, Serial No. 417,535.

The present improvement contemplates the provision of a novel form of plane structure, which renders the planes or wings 15 strong and durable, without materially increasing their weight.

With the above and other objects in view, the invention further includes the following novel features and details of construction, to be hereinafter more fully described, illustrated in the accompanying 20 drawings and pointed out in the appended claim.

In the drawings:—

Figure 1 is a fragmentary plan view illustrating the plane structure.

Figure 2 is a longitudinal sectional view of the same.

Referring in detail to the drawings, wherein like characters of reference denote 30 corresponding parts, the improved plane structure comprises spaced transverse strips 16 and spaced longitudinally disposed strips 17, the latter being spaced above and below the strips 16 and connected at their points of 35 intersection by fastening devices 18. These strips may be of any suitable or desired material, the object being to provide as light a structure as consistent with strength and rigidity. The upper and lower marginal 40 edges of the wings are surrounded by strips

19, which are also secured to the longitudinal and transverse strips by fastening devices similar to the fastening devices 18. This provides an exceedingly strong, light and rigid plane structure, which may be 45 shaped to conform to any desired outline or shape. The structure is covered with a covering 20 of suitable fabric, which is preferably arranged upon both the lower and upper surface of the frame work. 50

The invention is susceptible of various changes in its form, proportions and minor details of construction and the right is herein reserved to make such changes as 55 properly fall within the scope of the appended claim.

Having described the invention what is claimed is:—

An airplane wing structure embodying a center layer of transversely arranged spaced 60 strips in parallel relation to each other, a top layer of longitudinally arranged spaced strips in parallel relation to each other and at right angles to each other, the spacing of the strips in the top layer being equal to the 65 spacing of the strips in the center layer, a bottom layer corresponding in spacing and alignment to the top layer, said three layers being intimately and rigidly connected at the points of intersection, marginal strips 70 covering the longitudinal edges of said wings at the top and bottom and terminating in a sharp point at the outer end of the wing, and a fabric covering the top and bottom of said wing structure, whereby a single, plane wing of uniform thickness is obtained. 75

In testimony whereof I affix my signature.

FRANK B. VORACEK.
